UNITED STATES PATENT OFFICE

JOHN GALLATIN KEARBY AND ZEPHANIAH ROBINSON, OF MINERAL WELLS, TEXAS.

ELECTRIC CONNECTION FOR AUTOMOBILE-LAMPS

1,239,697.

Specification of Letters Patent. Patented Sept. 11, 1917.

Application filed May 18, 1916. Serial No. 97,433.

To all whom it may concern:

Be it known that we, JOHN G. KEARBY and ZEPHANIAH ROBINSON, citizens of the United States, residing at Mineral Wells, in the county of Palo Pinto and State of Texas, have invented certain new and useful Improvements in Electric Connections for Automobile-Lamps, of which the following is a specification.

10 Our invention has relation to an improvement in electric connections or plugs for incandescent electric lamps for automobiles, and in such connection it relates more particularly to the arrangement and construction of the lead in connections within the plug and leading to the terminals of the lamp.

Heretofore in automobile lamps wherein the current has been supplied from the magneto to the lights, perceptible variations in illumination were caused in stopping, starting or slowing down. In other words if the lamps were arranged so as to give full illumination only when full speed of the automobile was transferred to the magneto, then when the automobile was traveling at a low or relatively low speed the lights did not receive sufficient current and were dim.

20 In the usual practice of making connection between the terminals of the magneto circuit and the terminals of the lamp, a plug of hard rubber, or similar insulating material, inclosed two relatively large wires of conducting metal and each wire connected one terminal of the magneto circuit with one terminal of the lamp.

We have found that by rearranging these interior conductors within the plug and by connecting a terminal of the lamp not only 25 with a terminal conductor within the plug, but with the metallic socket holding the lamp, an increased and constant flow of current from the magneto to and through the lamp will be secured irrespective of the 30 variations in the speed at which the automobile travels and the magneto is run. The invention is particularly designed to improve the present lighting system on cars, which has the objectional feature that while the 35 engine is running fast the light is satisfactory, but when the engine is running slowly the lights are never bright enough.

In carrying out our invention, one relatively large metallic conductor within the 40 plug remains the same and leads the current directly from one terminal of the lamp, but

the other relatively large conductor is rearranged so that it initially leads from the second terminal of the magneto current directly to the first conductor within the plug. 45 The second terminal of the lamp communicates directly with an end of the second conductor wholly cut out or cut away from the other end of said conductor and this disconnected end of the second conductor 50 leads by pin or other suitable metallic connection to the metallic socket piece in which the lamp is inserted.

The nature and scope of our invention will be more fully understood from the following description taken in connection with the accompanying drawings forming a part hereof, in which—

Figure 1, is a side elevational view partly in section of an automobile headlight and lamp with conductor plug embodying the main features of my invention;

Fig. 2, is a similar view enlarged but with the plug sectioned to show the interior metallic conductors;

Fig. 3, is a detail sectional view taken to illustrate the detached end of the second conductor and its connection with the framing and metallic socket piece of the headlight, and

Fig. 4, is a cross-sectional view taken on the line 4—4 of Fig. 2.

Referring to the drawings, 1 represents the framing, 2 the reflector and 3 the incandescent electric lamp of an automobile headlight. The lamp 3 is of the usual carbon or metallic filament type and has in its base the two terminals for the lead in wires of the lamp. The lamp 3 locks by preference with a bayonet joint, in the metallic 50 socket piece 4 which is tubular and in electric contact with a sleeve 5 of the framing 1 of the light.

The socket piece 4 and sleeve 5 project beyond the framing 1 to receive one end of the 55 plug 6. This plug 6 is made of insulating material such as hard rubber and in its preferred form is in the shape of a rounded or square elbow.

The inner end of this plug 6 is provided with two metallic studs 7 and 8 whereof one, 7, forms the terminus for a relatively large metallic conductor 9, terminating at the outer end of the plug 6 in a binding post 10. The other metallic stud 8 penetrates some 60 distance into the interior of the plug in the form of a relatively large metallic conductor

11 and is connected with or terminates in a metallic pin 12 traversing the plug diametrically (see Fig. 3). This pin 12 enters and traverses a bayonet slot 13 at the outer end of socket piece 4 and is in electrical contact with said piece 4 and with the tube 5 of the framing 1.

At the outer end of the plug 6 adjacent to the binding post 10 is a second binding post 14 connected by a relatively larger conducting bridge piece 15 directly with the conductor 9 above binding post 10.

Between the base of lamp 3 and the inner end of plug 6 and within the socket piece 4 is secured a nonconducting disk 16 provided with and traversed by the two contact pins 17 and 18 so arranged that when all the parts are in position the pin 17 connects one terminal of the lamp 3 with stud 7 and pin 18 connects the other terminal of the lamp with stud 8.

To the binding post 10 leads one wire 19 of a magneto and to the binding post 14 another wire 20.

25 In the operation of our device either wire 19 or wire 20 may be utilized as a conductor for the current from the magneto. The other wire operates merely as a connection to the lamp on the other side of the automobile. Magneto is changed to a multiple system by the device. In case of either lamp breaking the other will continue to burn. The return from the lamp is to the framing 1. In actual use this arrangement of the 35 conductors in the plug results in increased light from the lamp and in a steadiness of illumination under varying speed of the vehicle which has heretofore been absent.

Having thus described the nature and objects of our invention what we claim as new and desire to secure by Letters Patent is—

40 1. An electric connection for automobile lamps consisting of a plug of insulating material, a relatively large conductor extending through the plug and positioned to connect with a terminal of the lamp, an electric conductor connecting with the framing of

the lamp and extending part way into the plug, a relatively short conductor connected to the latter conductor and positioned to connect with the other lamp terminal, and a conductor extending only part way into the plug and connected to the first named conductor.

2. An electric connection for automobile lamps consisting of a plug of non-conducting material, two binding posts embeded in the plug and arranged so that one receives a wire from the magneto and the other receives a wire leading to the lamp on the other side of the automobile, a relatively large conductor traversing the plug and forming an extension for one of the binding posts, the other post being electrically connected with the aforesaid conductor, an electric conductor arranged to connect with one of the terminals of the lamp, and an electrical conductor leading from the aforesaid conductor to the socket piece or frame of the lamp.

3. An electric connection for automobiles, consisting of a plug of non-conducting material, an electrical conductor traversing the plug, a second electrical conductor only partially traversing the plug, and arranged to 75 contact with a terminal of the lamp, an electrical conductor from the lamp frame or socket piece to the aforesaid short conductor and a conductor extending only part way into the plug and connected to the conductor which traverses the plug.

4. The combination of a non-conducting plug, a relatively large conductor extending through the plug, a second conductor extending only partially through the plug, the two conductors being bridged within the plug, one of the conductors being adapted to connect with a terminal of a lamp and with a source of electric current substantially as set forth.

In testimony whereof we have signed our names to this specification.

JOHN GALLATIN KEARBY.
ZEPHANIAH ROBINSON.
